PROPELLING MEANS

Allison R. Peirce, El Paso, Tex.

Application October 29, 1943, Serial No. 508,202

7 Claims. (Cl. 170—174)

The invention relates to screw-type propellers and while the present disclosure is directed to a marine propeller, the invention is also useable on aircraft.

One object of the invention is to provide a novel screw-type propelling means which may be reversed without reversing the direction in which it is driven.

Another object is to provide a novel screw-type propeller, the pitch of which may be varied at will.

A still further object is to provide a comparatively simple and inexpensive construction, yet one which will be efficient and reliable.

With the foregoing in view, the invention resides in the novel subject matter hereinafter described and claimed, description being accomplished by reference to the accompanying drawings.

Figure 1 is a fragmentary side elevation of the stern portion of a ship, partly broken away, showing one form of the invention, the propeller being set to drive the ship forwardly.

Fig. 2 is a vertical transverse section on line 2—2 of Fig. 1.

Fig. 3 is a fragmentary view similar to Fig. 1 but showing the propeller set to drive the ship rearwardly.

Fig. 4 is a view similar to Fig. 1 but illustrating a different form of the invention.

Fig. 5 is a transverse sectional view on line 5—5 of Fig. 4.

Fig. 6 is a detail longitudinal sectional view on line 6—6 of Fig. 5.

While the features of construction shown in the drawings will be rather specifically described, it is to be understood that the present disclosure is illustrative rather than limiting, to a large extent.

In the drawings above briefly described, 10 denotes a spiral spring metal propeller blade, the inner or apex end of which is suitably secured at 11 to a propeller shaft 12 of a ship 13. A rigid ring 14 extends circumferentially of the base end of the spiral propeller blade 10 and is secured to the same. Suitable mounting means is provided for this ring 14 and it will be seen that by relatively shifting this mounting means and the shaft 12, the spiral blade 10 may be sprung into the form of a forwardly pitched conical spiral as in Figs. 1 and 4, or into the form of a rearwardly pitched conical spiral as seen in Fig. 3. The blade preferably is of a width that decreases from its base to its apex, so that it is relatively open, and by making it of resilient

material so that it may be flexed, its apex end may move through and be positioned on either side of the plane of its base end. Thus, with the propeller shaft 12 driven in one direction only, the ship may be propelled forwardly or rearwardly at will. Moreover, it will be seen that whether the blade 10 be set for forward propulsion or rearward propulsion, its pitch may be varied as desired. In both forms of the invention herein disclosed, the apex of the blade 10 is shifted axially with respect to its base for reversing or pitch changing, but it will be seen that this is not essential for the same effect could be obtained by shifting the outer end or base of said blade axially with respect to its inner end or apex.

In the present disclosure, the driving means for the propeller shaft 12 includes coaxial gears 15 and 15', gear 15 being driven by an engine-driven shaft 16 while gear 15' is slidably keyed upon the shaft 12, the key-way being shown at 17 in Figs. 1 and 4. As the shaft is axially shifted through the gear 15' to spring or flex the propeller blade 10 as above explained, suitable provision is made for holding said gear 15' against movement with the shaft. Collars 18 at opposite sides of the gear 15' are shown for this purpose.

The shifting means for the shaft 12 may be of any appropriate nature. For illustrative purposes, a screw 19 has a swiveled connection 20 with the shaft, and said screw is engaged by a suitably mounted nut 21 having a hand wheel 22 by means of which it may be rotated. 23 denotes a bearing in which the nut is rotatably and non-slidably mounted.

In the form of construction shown in Figs. 1, 2 and 3, the ring 14 is rotatably mounted in suitable bearing forks 24 which are secured to the ship 13. In Figs. 4, 5 and 6, however, the ring

40 14 is provided with angular arms 25 which are circumferentially spaced and extend inwardly to a collar 26 to which they are suitably secured. The shaft 12 extends slidably through this collar 26 and is slidably keyed to it. The shaft 12, 45 collar 26, arms 25, ring 14 and propeller blade 10 are thus rotatable as a single unit. At 27, I have shown a key-way in the shaft 12 and at 28 (Fig. 5) have illustrated a key carried by the collar 26 and engaging said key-way to establish a driving connection between said sleeve and shaft. The sleeve may be held against axial shifting by any preferred means. A shell 29 is shown surrounding the front portion of said sleeve and secured to the ship 13. This shell

50 carries studs or the like projecting into a periph-

55

eral groove 31 in the sleeve 26, as shown in Fig. 6.

Instead of fixing the shell 29 to the ship and having the shaft 12 slide to adjust and reverse the propeller blade 10, it would of course be possible to non-slidably mount said shaft and to make provision for shifting said shell forwardly and rearwardly to attain the same results. Similarly, in Figs. 1 to 3, the shaft 12 could be non-slidably mounted and provision made to forwardly and rearwardly shift the mounting forks 24 of the ring 14, to adjust and reverse the propeller blade.

From the foregoing, taken in connection with the accompanying drawings, it will be seen that novel and advantageous provision has been made for carrying out the objects of the invention. Whenever the inner end of the spiral spring metal blade 10 is in advance of the ring 14, with the shaft 12 rotating as indicated by the arrows in Figs. 1 and 3, forward propulsion will be obtained, and the pitch of the propeller blade may be varied at will by longitudinally adjusting said shaft 12 by rotating the hand wheel 22 in one direction or the other. Whenever the inner end of the blade 10 is behind the ring 14, (see Fig. 3), with the shaft 12 rotating in the same direction as before, rearward propulsion will be obtained, and the pitch of said blade may be varied as required, it being of course understood that the pitch variance will change not only the speed of the vessel but will vary the propulsive power exerted by the propeller.

Attention is again invited to the possibility of making variations within the scope of the invention as claimed.

I claim:

1. A propelling means comprising an open spiral spring propeller blade, the apex end of which is movable through the plane of its base end, driving means connected with one end of said spiral propeller blade, mounting means for the other end of said spiral propeller blade, and means for relatively shifting said driving means and mounting means axially to spring said spiral propeller blade into the form of a forwardly pitched conical spiral when desired and into the form of a rearwardly pitched conical spiral when desired, whereby said propeller blade may drive a vehicle either forwardly or rearwardly without reversing its direction of rotation.

2. A propelling means comprising an open spiral spring propeller blade, the apex end of which is movable through the plane of its base end, a propeller shaft coaxial with said spiral propeller blade and secured to the apex thereof, mounting means for the base of said spiral propeller blade, and means for relatively shifting said propeller shaft and mounting means axially to spring said spiral propeller blade into the form of a forwardly pitched conical spiral when desired and into the form of a rearwardly pitched conical spiral when desired, whereby said propeller blade may drive a vehicle either forwardly or rearwardly without reversing its direction of rotation.

3. A propelling means comprising an open spiral spring metal propeller blade, the apex end of which is movable through the plane of its base end, a propeller shaft coaxial with said spiral propeller blade and secured to the apex thereof, a rigid ring extending circumferentially of said spiral propeller blade and secured to the base thereof, mounting means for said ring, and means for relatively shifting said propeller shaft and mounting means axially to spring said spiral propeller blade into the form of a forwardly pitched conical spiral when desired and into the form of a rearwardly pitched conical spiral when desired, whereby said propeller blade may drive a vehicle either forwardly or rearwardly without reversing its direction of rotation.

4. A propelling means comprising an open spiral spring metal propeller blade, the apex end of which is movable through the plane of its base end, a propeller shaft coaxial with said spiral propeller blade and secured to the apex thereof, a rigid ring extending circumferentially of said spiral propeller blade and secured to the base thereof, fixed bearing means in which said ring is rotatably mounted, and means for axially sliding said shaft.

5. A propelling means comprising an open spiral spring metal propeller blade, the apex end of which is movable through the plane of its base end, a propeller shaft coaxial with said spiral propeller blade and secured to the apex thereof, a rigid ring extending circumferentially of said spiral propeller blade and secured to the base thereof, a collar surrounding said propeller shaft and spaced from the plane of said ring, circumferentially spaced arms secured to said ring and collar, and means for axially sliding said propeller shaft and collar relatively to each other.

6. A propelling means comprising an open spiral spring metal propeller blade, the apex end of which is movable through the plane of its base end, a propeller shaft coaxial with said spiral propeller blade and secured to the apex thereof, a rigid ring extending circumferentially of said spiral propeller blades and secured to the base thereof, a collar surrounding said propeller shaft and spaced from the plane of said ring, circumferentially spaced arms secured to said ring and collar, means for holding said collar against axial shifting, and means for axially shifting said propeller shaft.

7. A propelling means comprising a spiral propeller blade of resilient material, said blade decreasing in width from its base to its apex to permit its apex end to be positioned on either side of the plane of its base end, driving means connected with one of the ends of said blade, mounting means for the other end of said blade, and means for relatively shifting said driving means and mounting means axially to position the apex end of the blade on either side of the plane of the base end thereof.

ALLISON R. PEIRCE.
